(57) **CLAIM**

The ornamental design for a tail lamp housing unit, as shown and described.

DESCRIPTION

FIG. 1 is a rear perspective view of a tail lamp housing unit showing our new design.

FIG. 2 is a front perspective view thereof.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a rear perspective view showing environmental structure thereof.

Contour lines are intended to represent three-dimensional contours of the design, and are not intended to indicate surface decoration.

The broken lines are for the purpose of illustrating environmental structure for the claimed design and form no part of the claimed design.
